UNITED STATES PATENT OFFICE.

JOHN H. HOWARD, OF MINNEAPOLIS, MINNESOTA, ASSIGNOR TO EZRA GARFIELD STEGNER, JAMES S. INGALLS, AND JOHN H. HOWARD, TRUSTEES.

DESIGN FOR A LENS FOR HEADLIGHTS.

57,909.

Specification for Design.

Patented May 17, 1921.

Application filed August 2, 1920. Serial No. 400,872. Term of patent 3½ years.

To all whom it may concern:

Be it known that I, JOHN H. HOWARD, a citizen of the United States, residing at Minneapolis, in the county of Hennepin and State of Minnesota, have invented a new and original Design for a Lens for Headlights, of which the following is a specification, reference being had to the accompanying drawings, forming a part thereof, which shows the same in front or face elevation.

The numeral 1 indicates a crescent shaped piece of opalescent green glass having irregular surfaces. The main glass section of the lens has a ground surface 2 and a finely

corrugated surface 3. The two glass sections are placed within a marginal channel frame 4, and a curved bar 5 is interposed between the adjacent edges of the two glass sections and extends from one side to the other of the marginal frame 4.

I claim:

The ornamental design for a lens for headlights, as shown.

JOHN H. HOWARD.

Witnesses:

CLARA DEMAREST,
WINIFRED I. WARD.
